UNITED STATES PATENT OFFICE.

PHILIP GROENENSTEIN, OF CLEVELAND, OHIO.

DESIGN FOR A COMBINED GLARE SHIELD AND A SUPPORTING BRACKET THEREFOR.

Application filed December 24, 1926. Serial No. 20,148. Term of patent 7 years.

To all whom it may concern:

Be it known that I, PHILIP GROENENSTEIN, a citizen of the United States, residing at Cleveland, in the county of Cuyahoga and State of Ohio, have invented a new, original, and ornamental Design for a Combined Glare Shield and a Supporting Bracket Therefor, of which the following is a specification, reference being had to the accompanying drawing, forming a part thereof.

In the drawings Fig. 1 is a front elevation and Fig. 2 is a side elevation of a combined glare shield and a supporting bracket therefor showing my new design.

I claim:

The ornamental design for a combined glare shield and a supporting bracket therefor as shown.

PHILIP GROENENSTEIN.
